UNITED STATES PATENT OFFICE

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A CORPO-
RATION OF NEW JERSEY

FASTENING-INSERTING MACHINE

Application filed September 11, 1928, Serial No. 305,239, and in Great Britain October 8, 1927.

This invention relates to fastening inserting machines, and more particularly to machines for inserting previously formed metallic fastenings, such as loose nails, in parts of boots and shoes.

In one aspect, the invention consists in improvements in this type of machine designed to improve its simplicity of construction, speed of operation and accuracy in handling and driving the fastenings. In another aspect, it consists in novel mechanism for handling nails of the type known as Cutlan bills and particularly Cutlan bills of a small size which have never been handled previously in automatic fastening inserting machines.

An important feature of the invention consists in a novel arrangement of driver and raceway in accordance with which the driver is utilized to close the raceway in the stopped position of the machine and also in certain other positions in its path of movement so that the driver itself holds back, during a part of the cycle, the row of fastenings arranged in the raceway for insertion. As herein shown, the driver is given a preliminary movement in the direction of its driving stroke into raceway-closing position for the purpose of retaining the fastenings while the separator is retracted. In this way, the raceway is left clear for the fastening released by the separator to advance directly into engagement with the side of the driver under impulse of the jar of the driving stroke.

In transferring a fastening into the driver passage preparatory to inserting it in the work, it sometimes happens that the fastening becomes misplaced so that it has a tendency to jam in the passage. This is particularly the case in handling short Cutlan bills as a driver passage of sufficient size to admit the head does not positively control the position of the point of the bill. With these conditions in view, another feature of the invention consists in a driver passage having one side closed by a hinged section which is adapted to yield in the event of a fastening being improperly placed for driving and also affords a convenient means of access to the driver passage in case of stoppage.

Still another feature of the invention con-

sists in closing the bottom of the space through which the fastening is moved by the separator in its delivery to position beneath the driver by a surface which tends to direct the fastening points to line with the driver. The separator itself is also of novel design, comprising two branches, one beveled away from the raceway to separate the fastenings therein and the other comprising an elongated extension having an upwardly sloping face for directing the shanks into line with the driver in the manner already explained.

These and other features of the invention will be best understood and appreciated from the following description of a preferred embodiment thereof, selected for purposes of illustration and shown in the accompanying drawings, in which

Fig. 1 is a view in elevation of the machine head;

Fig. 2 is a view in front elevation, on an enlarged scale, of the driver and separator operating cam;

Fig. 3 is a plan view of the separator and associated parts;

Fig. 4 is a view in elevation of the separator and associated parts with the cover plate removed;

Fig. 5 is a similar view showing in addition the raceway and driver;

Fig. 6 is a fragmentary view of portions of the separator operating mechanism;

Fig. 7 is a front view of the parts shown in Fig. 3; and

Fig. 8 is a diagram showing the driver and separator movements.

The machine is herein shown as adapted to handle the particular nails known as Cutlan bills, of which the chief characteristics are that the head and shank are rectangular and the head merges directly into the shank at an angle on all four sides of 23° or thereabouts. Cutlan bills are commonly used in a series of sizes in which the larger dimension of the head varies between 0.150 and 0.185", each size being made in lengths as required, varying between $\frac{1}{4}$ and $\frac{5}{8}$ ". The particular Cutlan bill which for the first time is handled by the mechanism of my invention is smaller in its cross section than any heretofore used,

its head dimensions being 0.111 by 0.080"; its shank dimensions being 0.082 by 0.043"; the height of the sloping sides of the head 0.040" and the overall length of the bill $1\frac{1}{2}$ ".

As is customary in inserting all forms of rectangular cross section nails, it is desired to insure that each nail of a row is driven in a definite angular position. In the case of Cut-lan bills, this position is one in which the larger dimension of the head lies perpendicular or normal to the line of the bills. For this reason, the raceway for supplying the bills is of sufficient width only to admit the smaller dimension of the rectangular shank and the direction of the work feed is at right angles to the movement of the bills in leaving the raceway.

The invention is shown as embodied in a machine of the general type of that disclosed in U. S. Patent No. 490,624, granted January 24, 1893, on an application of L. Goddu, to which reference may be had for details of construction not directly concerned with the present invention.

As shown in the drawings, the raceway comprises a pair of rails 2 spaced apart to receive bills of the dimension to be inserted and curving at its discharge end at right angles to the main part of the raceway, as shown in Fig. 3. A separator 3, comprising a bar with a forked end, is arranged to slide across the discharge end of the raceway, being mounted in an undercut guideway 4 formed in the raceway end 6 and so disposed that its outer surface is flush with the end of the raceway. The movement of the separator, therefore, is in a path at right angles to that of the usual separator. The outer face of the guideway 4 is closed by a cover plate 7 and extending through the inner wall of the guideway 4 is a slot opening into a parallel guideway in the rear surface of the raceway end 6. An actuating slide 10 is mounted in this second guideway and connected by screws 8 and 9 to the separator 3. The slide 10 is operated by a bell crank lever 11 pivotally mounted upon a stud 12 set in the swinging head of the machine. One arm 13 of the lever 11 is engaged between lugs 14 and 15 which project from the slide 10 and the other arm 16 is received in a slot cut in the lower end of a swivel stud 17 carried in the lower end of a lever 18. The lever 18 is mounted in the machine head upon a transverse spindle and is arranged to be swung in one direction by a coil spring 5 and in the other by a cam 29, which will be presently described.

The main portion of the raceway is covered by an adjustable cover 20 adapted to slide and swing clear of the raceway when required in the manner described in U. S. Patent No. 1,474,368, granted November 20, 1923 on application of A. E. Jerram. Between the cover 20 and the block forming the gateway of the nail pot is mounted a covering finger 21.

The driver 22 is carried by a driver bar 27 arranged to be actuated by a torsion spring 44 in the manner usual in this type of machine. It is, however, so located with respect to the discharge end of the raceway 2 that in certain positions in its cycle of movement it closes the raceway and prevents the line of bills from advancing by engaging the endmost bill. The driver, accordingly, cooperates with the separator in controlling the movement of the bills presented successively for insertion.

The separator-actuating lever 18 carries at its upper end a roller 28 which is held by the action of the spring 5 against an annular cam flange on the cam disk 29. The timing of the cam will be apparent from an inspection of the diagram shown in Fig. 8, which represents one cycle of movement, comprising 360°. It will be apparent that the machine stops with the separator slightly advanced but in the act of being retracted, that is to say, with the cam in substantially the position shown in Fig. 2 and the cam roller 28 lifted slightly by the cam surface 42. At the same time, the driver occupies its lowermost position and is effective to close the raceway, as already explained, and the awl 57 is lifted.

When the machine is started, the separator first completes its return movement and then, after about 180°, the driver is elevated. As its upward movement continues the separator is advanced by the action of the cam surface 23 so that it moves forward and enters between the shanks of the two endmost bills in the raceway. This partial forward movement of the separator, which takes place when the portion 23 of the cam 29 reaches the roll 28, occurs when the driver has risen sufficiently to clear the bills in the raceway which, up to that moment, the driver has been the sole means of restraining. The separator dwells in its partially forward position for about 10° while the flat portion 24 of the cam passes beneath the roller 28. During this dwell, the driver is being lifted to clear the bills and as it reaches the limit of its stroke the separator movement is continued by the action of the cam surface 25 and the endmost bill is positively advanced by the advancing wedge-shaped end of the separator into the driver passage 33 in alignment with and below the driver. The separator remains in position at the limit of its forward movement for about 35° while the flat portion 40 passes beneath the cam roller 28 and is then retracted to a position in which the raceway is uncovered as the sloping portion 42 of the cam passes beneath the roller.

The lower fork of the separator 3 comprises an extension 26 which is long enough to pass across the raceway in all positions of the separator in its reciprocation. The extension 26 is located below the points of the bills in the raceway and has a beveled upper surface which acts as a closure for the bot-

tom of the space across which each bill is moved by the action of the separator. This surface is beveled upwardly, as shown in Fig. 7, toward the outer surface of the raceway 2 and serves to aid to tilt across the driver path the point of a bill leaving the raceway.

The driver 22 is arranged to be lifted by a cam 30 on the cam disk 29, as is usual in machines of this type, but instead of having a concentric acting face the cam 30 drops off so as to allow the driver to descend a short distance from its uppermost position before actually being released for its driving stroke. The actual distance through which the driver is lifted is also reduced from that which is usual in this type of machine by employing a driver lifting block 32 which is reduced in height at one side, as shown in Fig. 2. The driver 22 is arranged so that when it is lifted to its highest point its lower end will just clear the bills in the raceway and the short preliminary descending movement permitted by the cam 30 in its action on the beveled surface 41 of the lifting block permits the driver to overlap and hold back the row of bills in the raceway as the separator is retracted. This condition of affairs is shown in Fig. 5 and also in Fig. 2 where the parts occupy the position in which the driver is just about to drop, the cam 30 being shown at the moment of moving clear from under the lifting block 32.

During its driving stroke and until the separator 3 again traverses the raceway outlet, the driver itself forms by its rear side the closure of the discharge end of the raceway. The jar of the driver in falling acts to move the row of bills downward in the raceway and brings the endmost bill forward against the side of the driver. The action of the driver in rising tends by friction against the head of the endmost bill to tilt its shank well forward and across the path of the separator.

The driver throat 33 opposite to the delivery end of the raceway is closed by a hinged door 34, held normally shut by a spring plunger 35 mounted in the separator cover 7 and having a pin 46 projecting outwardly through the cover by which the plunger may be retracted when it is desired to expose the driver throat. The contacting surfaces of the spring plunger 35 and the door 34 are beveled so that in the event of a bill becoming misplaced and trapped by the driver, the door 34 can spring open, thus avoiding breakage. Below the upper portion 33 of the driver throat there is provided a spring section 37 of the construction shown in U. S. Patent No. 999,203, granted August 1, 1911, on an application of Bryant and Underwood. Each bill delivered from the raceway by the separator is retained in the throat by the friction of the spring section 63 until actually inserted.

In order the better to arrange the bills in the raceway for the action of the separator 3 upon them, a presser member is arranged to act upon the heads of the two endmost bills in the raceway. This member comprises a finger 50 which is pivoted at its rear end upon a transverse stud 51 projecting from the rear side of the raceway end 6. The other end 52 is located above the heads of the bills and is normally urged into engagement with them by a compression spring 53. Mounted upon the finger 50 is a roller 54 arranged over the separator actuating slide 10. The upper surface of the slide 10 is formed with a cam projection 55, as shown in Fig. 4, which, when the slide and separator are moved back so that the latter clears the raceway, contacts with the roller 54 and lifts the end 52 of the finger, thus allowing the advancing bills to pass freely along to the driver. The under side of the bill-engaging end 52 of the finger is formed, as shown in Fig. 7, with two angular faces divided by a ridge 56. The ridge 56 is thus pressed down between the heads of the two endmost bills in the raceway and acts to tilt the shanks of both of them away from each other, providing a space between them for the entrance of the separator wedge.

It will be understood that the machine includes in its organization an awl 57 operated, as set forth in said Patent No. 490,624, to perforate the work at one side of the fastening inserting position and then to feed the work to bring the hole into alignment with the driver. These operations occur in the 180° of machine cycle which elapses before the driver begins to move as indicated in Fig. 8.

That feature of the invention in accordance with which the driver is located close to the raceway and utilized to retain the series of bills therein is of advantage both from the standpoint of simplicity in the construction of the machine and in reducing the distance through which the bill must be moved in passing from the raceway to its inserting position, and also in that it affords a positive and direct control of the bill. All of these factors contribute to the production of a high speed machine which may be relied upon to handle bills or similar fastenings with uniformity and accuracy.

Having thus described my invention, what I claim as new and desire to secure by Letters Patent is:

1. A fastening inserting machine having, in combination, a raceway for loose fastenings, a driver, means for reciprocating the driver in a path adjacent to the end of the raceway to insert fastenings in a work piece presented to the machine constructed and arranged to cause the driver to move from a position clear of the raceway to a position opposite the end of the raceway thereby retaining the fastenings in the raceway and thereafter to complete its fastening inserting stroke, a separator movable in a path extend-

ing transversely of the direction of movement of the fastenings as they emerge from the raceway, and means for moving the separator in its path constructed and arranged to withdraw the separator from the raceway while the driver is maintained opposite the end of the raceway whereby a fastening is freed to pass the separator and to move into engagement with the driver by which it is retained in the raceway temporarily.

2. A fastening inserting machine having a raceway for headed fastenings, a reciprocatory driver so disposed in lowermost position as to close said raceway, and a separator operating to move the fastenings one by one from the raceway into the path of the driver when the latter is lifted, said separator being movable before the machine reaches its stopping position to clear the way for a fastening to pass along the raceway until stopped by contact with the driver.

3. A fastening inserting machine having a raceway for loose fastenings, a driver normally closing said raceway, spring-actuated means for imparting a driving stroke to the driver, and a cam for moving said driver in opposition to said spring-actuated means designed to permit the driver to reassume a raceway-closing position prior to its driving stroke, the driver acting in the last-named position as the sole means for retaining the fastenings in the raceway.

4. A fastening inserting machine having a raceway for headed fastenings, a driver movable adjacent to the delivery end of the raceway and closing the same in certain positions, a separator arranged to close the raceway when the driver is at the limit of its upward movement, and means for moving the driver during each cycle in the direction of its driving stroke to overlap and hold back oncoming fastenings in the raceway, the driver acting in the last-named position as the sole means for retaining the fastenings in the raceway.

5. A fastening inserting machine having a raceway for loose fastenings, a separator movable in a path at right angles to the direction of movement of the fastenings as they emerge from the raceway, and means for moving the separator automatically first across the end of said raceway to place a fastening in driving position and then back again to clear the raceway in the stopped position of the machine.

6. A fastening inserting machine having a raceway, a driver passage adjacent thereto, and a separator for moving fastenings from the raceway to the driver passage having a portion permanently closing the space beneath the fastening in its movement to the driver passage.

7. A fastening inserting machine having a raceway for loose fastenings, a driver passage adjacent thereto, and a separator hav-

ing an extended portion disposed at all times beneath the raceway for directing the fastening point toward the driver passage.

8. A fastening inserting machine having a raceway for loose fastenings, a driver, and a separator cooperating therewith in controlling the movement of the endmost fastening into driving position, said separator being movable to engage the shank of said fastening while the driver moves upwardly, being thereafter arrested while the driver completes its upward stroke, and completing its fastening-delivering movement after the driver reaches its uppermost position.

9. A fastening inserting machine having a raceway for loose fastenings, and a separator having upper and lower branches, the upper branch being beveled away from the raceway and the lower branch extending beyond the upper branch and having an upwardly beveled portion for deflecting the fastening point away from the raceway.

10. A machine for inserting Cutlan bills having a raceway, a reciprocatory driver arranged to close the raceway in certain positions, a separator, and means for imparting a preliminary movement to the driver in the direction of its driving stroke into raceway-closing position for the purpose of retaining the bills while the separator is retracted, thereby permitting the bills in the raceway to advance into engagement with the side of the driver under the impulse of the jar of the driving stroke.

In testimony whereof I have signed my name to this specification.

WILLIAM THOMAS BUCKINGHAM ROBERTS.
